UNITED STATES PATENT OFFICE

ALVIN G. SHERMAN, OF DETROIT, MICHIGAN, ASSIGNOR TO DETROIT VAPOR STOVE COMPANY, OF DETROIT, MICHIGAN, A CORPORATION OF MICHIGAN

DESIGN FOR A TEMPERATURE REGULATOR FOR STOVES

Application filed November 7, 1929. Serial No. 33,362. Term of patent 7 years.

To all whom it may concern:

Be it known that I, ALVIN G. SHERMAN, a citizen of the United States, residing at Detroit, Wayne County, Michigan, and whose post-office address is 12345 Kercheval Avenue, Detroit, Michigan, have invented a new, original, and ornamental Design for Temperature Regulator for Stoves, of which the following is a specification, reference being made to the accompanying drawings, forming part thereof.

Fig. 1 is a front elevation of the article showing my new design.

Fig. 2 is a side elevation of the article shown in Fig. 1.

I claim:

The ornamental design for a temperature regulator for stoves, substantially as shown.

ALVIN G. SHERMAN
